UNITED STATES PATENT OFFICE

HARDIN D. THWEATT, OF HUDSON, OHIO, ASSIGNOR TO THE ADAMSON MACHINE COMPANY, OF AKRON, OHIO, A CORPORATION OF OHIO

RIVETING PRESS

Application filed May 3, 1928. Serial No. 274,791.

The invention relates to riveting presses, and may be especially adapted to a press for riveting laminations such as poles for motors, generators and the like; although it is equally adapted for riveting any kind of plates or laminations.

It is common practice in riveting together laminations such as the poles for large motors, generators and the like, to clamp the laminations together by means of clamps and upset the rivets by hand or singly by a press.

It is present practice to do such riveting with rivets having a head already formed upon one end before the rivets are inserted through the laminations, the other end of the rivet being upset in the riveting operation. As a result, one end portion of each rivet is not enlarged, by the upsetting, to fill the holes in the laminations.

20 The object of the improvement is to provide a press of this character having means for centering the rivets through a pack of laminations whereby fixed amounts of each rivet may project beyond opposite sides of 25 the pack of laminations, means being provided for pressing the laminations tightly together and separate means being provided for upsetting the rivets at both sides of the laminations.

30 An embodiment of the invention such as adapted for riveting laminations is illustrated in the accompanying drawings, in which

Figure 1 is a side elevation of the improved riveting press;

Fig. 2, a vertical sectional view of the same;

Fig. 3, an enlarged fragmentary section through portions of the upper head, bolster, 40 insert plates, riveting pins and rams, showing a pack of laminations in position to be riveted; and

Fig. 4, a similar view, showing the parts in the operated position.

45 Similar numerals refer to similar parts throughout the drawings.

The improved press may comprise the base 1, mounted upon any suitable support such as indicated generally at 2, which may 50 be located within a pit or the like, as at 3,

the top of the base being substantially flush with the floor level 4.

Upright guide rods 5 are connected to the corner portions of the base and support the head, shown generally at 6, in fixed spaced relation to the base, at their upper portions.

The base may be provided at each side with a fluid cylinder 7 within which is located a ram or piston 8, supporting the end portions of the bolster 9, for vertical movement between the guide rods 5.

55 A fluid supply pipe 10 communicates with both of the fluid cylinders 7, as indicated at 11, and a valve 12 controls the admission of fluid under pressure to said cylinders. The amount of pressure in the cylinders may be indicated as by the gauge 13.

An insert plate 14 is carried by the bolster 9 and may be provided with the shouldered portion 15 seated within the recess 16 of 60 the bolster and movable therewith.

65 A plurality of riveting pins 17, corresponding in number and position to the rivets to be headed, are slidably located through openings 18 formed in the insert plate. Each of these openings is enlarged at its upper portion as at 19 to receive the enlarged head 20 of the riveting pin, which is adapted to normally rest upon the shoulder 21 of the openings to prevent the pin from dropping 70 downward out of the insert plate.

75 A fluid cylinder 22, preferably of considerably larger diameter than the cylinders 7, is centrally located in the base 1 and provided with a ram or piston 23, the upper end of 80 which may be slightly reduced as at 24 and extended through the central opening 25 in the bolster, a ram cap 26 being adapted to be engaged by the upper end of the ram.

85 This ram cap is arranged to be seated upon the shoulder 27 in the bolster to limit the downward movement of the ram cap with reference to the bolster, whereby the space between the bottom of the insert plate 14 and the top of the ram cap 26 is normally constant.

90 A fluid supply pipe 28 communicates with the cylinder 22, admission of fluid thereto being controlled as by the valve 29. A gauge 100

30 may be provided for indicating the amount of pressure in the cylinder.

An upper insert plate 31 is fixed within the upper head 6 of the press and provided with a plurality of riveting pins 32, corresponding in number and position to the pins 17 and slidably located through the vertical opening 33 in the insert plate.

Heads 34 are provided upon the upper ends 10 of the pins 32, adapted to contact with the shoulders 35, in the upper ends of the openings 33, in order to limit the downward movement of the pins.

These pins as well as the pins 17 may be 15 shaped at their riveting ends to produce the desired shape of rivet head. In the drawings these pins are shown shaped as at 36 adapted to form heads upon the rivets as shown at 37 in Fig. 4, this being one form 20 of rivet head that may be made thereby.

A fluid cylinder 38 is carried by the upper head 6 and connected to the gauge 30, and valve 29, as by a pipe 39, by means of which fluid may be admitted simultaneously to the 25 cylinders 22 and 38.

A piston or ram 40 is mounted within the cylinder 38 and adapted to operate upon the ram cap 41 to move the same downward toward the insert plate 31, the ram cap contacting 30 with the upper ends of the riveting pins 32.

With the press in the normal or initial position, as shown in Fig. 2, a pack of laminations to be riveted, with the rivets located 35 therethrough, is placed in position upon the lower insert plate 14, the rivets registering with the riveting pins 17.

A fragmentary portion of such a pack of laminations is shown at 42 in Figs. 3 and 4. 40 The laminations are provided with apertures 43 registering with each other to receive the rivets 44.

As shown in Fig. 3, these apertures are slightly larger than the rivets, permitting 45 them to be easily and readily inserted through the laminations by hand.

In placing these rivets through the laminations it is impossible to accurately center each rivet through the laminations, that is to say, 50 equal amounts of each rivet do not ordinarily protrude from opposite sides of the pack of laminations.

With the construction of press disclosed herein, this lack of uniformity of the amount 55 of rivet projecting from each side of the laminations is compensated for. This is accomplished by permitting movement of the ram caps 26 and 41 with respect to the insert plates 14 and 31 respectively, and limiting the maximum movement between the ram caps 60 and insert plates as by the shoulders 27 and 45 in the bolster and upper head respectively.

The distance between the top of the insert 65 plate 14 and the shoulder 27 is constant and the distance between the bottom of the insert

plate 31 and the shoulder 45 is constant. These distances must be equal where the heads to be formed at both ends of the rivets are the same.

Thus when the pack of laminations is 70 placed upon the lower insert plate, in proper position as above described, and fluid admitted to the cylinders 7, the rams 8 will raise the bolster 9, bringing the top of the pack of laminations into contact with the upper insert plate 31, sufficient pressure being applied to clamp these laminations tightly together in the position shown in Fig. 3.

Opposite ends of the rivets 44 will contact 75 with the upper and lower riveting pins 32 and 17 respectively and these rivets will be properly centered through the pack of laminations as illustrated in Fig. 3.

This is accomplished by the lower riveting pins 17 being forced downward against the 80 lower ram cap 26 which rests upon the shoulder 27, while the upper riveting pins 32 will be forced upward, raising the upper ram cap 41 until it contacts with the shoulder 45.

Equal amounts of each rivet 44 will thus 85 project beyond each side of the laminations. The pressure is held upon the cylinders 7, holding the laminations clamped tightly together and pressure is then applied to the cylinders 22 and 38, raising the ram 23 and lowering the ram 40 simultaneously, with pressure equalized on both rams.

The movement of these rams forces the riveting pins 17 upward and the riveting pins 32 downward, riveting heads 37 upon the 90 rivets 44 as illustrated in Fig. 4.

All of these heads upon the rivets will be 95 of uniform size and shape, being formed from an equal amount of metal and furthermore, the rivets 44 will be shortened and slightly enlarged in diameter, causing the same to tightly fit within the openings 43 in the laminations as illustrated in Fig. 4.

The pressure is then released from all of 100 the cylinders and the parts permitted to return to the normal position when the riveted pack of laminations may be removed from the press.

From the above, it will be obvious that a plurality of rivets may be simultaneously 105 centered and riveted, clamping the laminations together in a single operation of the improved press.

Although the press is illustrated and described as a vertical press with the bolster and rams running vertically, it should be understood that the invention is not limited to a vertical press, but that the entire press may be located in a horizontal, or other position without departing from the spirit or sacrificing any of the advantages of the invention.

It should also be understood that the press is applicable to the riveting of any number of plates or laminations of any thickness and 110

shape, and of any material, metallic or non-metallic.

Although the press as illustrated is adapted to form similar heads upon each end of the rivet, it should be understood that in case it is desirable to form heads of different size or shape at opposite ends to the rivet, this may be accomplished by so spacing the shoulders 27 and 45, with reference to the respective insert plates, that the desired amount of each rivet will protrude through each side of the pack of laminations.

I claim:

1. A press including a fixed head, an insert plate in the head, riveting pins in the insert plate, a bolster movable toward and from the head, an insert plate in the bolster, riveting pins in said last named insert plate, ram caps movably mounted in the head and bolster for contact with the riveting pins, shoulders in the head and bolster for limiting outward movement of the ram caps, and means for moving the ram caps axially toward each other.

2. A press including a fixed head, an insert plate in the head, riveting pins in the insert plate, a bolster movable toward and from the head, an insert plate in the bolster, riveting pins in said last named insert plate, ram caps movably mounted in the head and bolster for contact with the riveting pins, shoulders in the head and bolster for uniformly limiting outward movement of the ram caps, and means for moving the ram caps axially toward each other.

3. A press including a fixed head, an insert plate in the head, riveting pins in the insert plate, a bolster movable toward and from the head, an insert plate in the bolster, riveting pins in said last named insert plate, ram caps movably mounted in the head and bolster for contact with the riveting pins, shoulders in the head and bolster for limiting outward movement of the ram caps, means for moving the bolster toward the head, and means for moving the ram caps axially toward each other.

4. A press including a fixed head, an insert plate in the head, riveting pins in the insert plate, a bolster movable toward and from the head, an insert plate in the bolster, riveting pins in said last named insert plate, ram caps movably mounted in the head and bolster for contact with the riveting pins, shoulders in the head and bolster for uniformly limiting outward movement of the ram caps, means for moving the bolster toward the head, and means for moving the ram caps axially toward each other.

5. A press including a fixed head, an insert plate in the head, riveting pins in the insert plate, a bolster movable toward and from the head, an insert plate in the bolster, riveting pins in said last named insert plate, ram caps movably mounted in the head and bolster for contact with the riveting pins, shoulders in the head and bolster for uniformly limiting outward movement of the ram caps, and means for moving the ram caps axially toward each other.

6. A press including a fixed head, an insert plate in the head, riveting pins in the insert plate, a bolster movable toward and from the head, an insert plate in the bolster, riveting pins in said last named insert plate, ram caps movably mounted in the head and bolster for contact with the riveting pins, shoulders in the head and bolster for uniformly limiting outward movement of the ram caps, and rams for moving the ram caps axially toward each other.

7. A press including a fixed head, an insert plate in the head, riveting pins in the insert plate, a bolster movable toward and from the head, an insert plate in the bolster, riveting pins in said last named insert plate, ram caps movably mounted in the head and bolster for contact with the riveting pins, shoulders in the head and bolster for uniformly limiting outward movement of the ram caps, and rams for moving the ram caps axially toward each other.

8. A press including a fixed head, an insert plate in the head, riveting pins in the insert plate, a bolster movable toward and from the head, an insert plate in the bolster, riveting pins in said last named insert plate, ram caps movably mounted in the head and bolster for contact with the riveting pins, shoulders in the head and bolster for uniformly limiting outward movement of the ram caps, and rams for moving the ram caps axially toward each other.

9. A press including a fixed head, an insert plate in the head, riveting pins in the insert plate, a bolster movable toward and from the head, an insert plate in the bolster, riveting pins in said last named insert plate, ram caps movably mounted in the head and bolster for contact with the riveting pins, shoulders in the head and bolster for uniformly limiting outward movement of the ram caps, rams for moving the bolster toward the head, and rams for moving the ram caps axially toward each other.

In testimony that I claim the above, I have hereunto subscribed my name.

HARDIN D. THWEATT.
